LOUIS STEINBERGER, OF NEW YORK, N. Y.

SAFETY STRAIN-INSULATOR.

1,206,158.

Specification of Letters Patent. Patented Nov. 28, 1916.

Application filed July 25, 1912. Serial No. 711,466.

To all whom it may concern:

Be it known that I, LOUIS STEINBERGER, residing at Brooklyn, county of Kings, city and State of New York, have invented certain new and useful Improvements in Safety Strain-Insulators, of which the following is a specification.

This invention relates to an insulator of the safety strain type adapted for use in general electric work, especially for the insulation of wires carrying currents of high voltage, and in instances where the insulator is subjected to a great mechanical strain, and the structure embodied comprises a pair of metallic disks arranged substantially concentric with each other and spaced apart by suitable insulating material, said disks having strain members of conducting material attached thereto in such manner as to tend to force said disks toward each other, against the intervening insulating material, in resisting the mechanical stresses to which the insulator is subjected.

Among the several objects of the invention are:

1. To provide the metallic anchoring members in the form of disks with elongated openings through the material thereof, of sufficient size to accommodate the strain members, especially to facilitate the assembling of the device, and to provide for an interlocking relation between each strain member, and its respective disk whereby the parts may be easily and cheaply assembled.

2. To provide an efficient interlocking joint between the strain members and the disks, by which each strain member may be connected to its respective disk by merely springing the parts together, and, further, so that when thus connected, the strain members will have no appreciable relative longitudinal movement, as well as no appreciable relative transverse movement.

3. To arrange the interlocking parts so that when interlocked, each leg of the U-shape strain member preferably employed, will be so connected with the disk as to be incapable of appreciable longitudinal or transverse relative movement irrespective of the presence of the other leg, or of any spring action between the legs.

4. To provide the interlocking parts, particularly adapted for use with the U-shape strain members preferably employed, whereby said strain members may be forced into position and thereby sprung, through the

spring action between the legs, into interlocking relation so that said spring action will coöperate with said interlocking means to prevent relative longitudinal movement between the parts.

5. To provide U-shape strain members adapted to be connected with anchoring disks and to form oppositely projecting shoulders, one on each leg of said U-shape strain member, adapted to engage one surface of said disk to prevent longitudinal movement of the strain member in one direction, and to form heads at the ends of said legs adapted to engage the opposite surface of said disk to prevent relative movement of said strain member longitudinally in the other direction, and to form the parts of such proportions that said shoulders and heads may be engaged with said disks to perform their functions by forcing the strain member through an opening in the disk, and thus spring the legs toward each other until the shoulders snap past the disk.

6. To form the heads on the legs of the strain members preferably of a wedge-shape adapted to engage wedge-shaped depressions in the disks in such manner as to prevent appreciable movement of the legs toward each other, once the shoulders have been snapped into interlocking relation.

7. To so shape the parts that one of the strain members may be placed in interlocking relation with its respective disk, that the other disk may be dropped over said first strain member, that said second strain member may then be linked with said first strain member and subsequently dropped into interlocking relation with said second disk, for the purpose of cheaply assembling the parts prior to the application of the enveloping insulating material for maintaining them in insulated relation, all as graphically set forth in Figs. 3 to 6 of the drawings.

8. To shape the disks and the coöperating parts of the strain members so that I am enabled, without weakening the structure, to cut away a much greater proportion of each disk, than has heretofore been possible, for permitting passage of the strain member of the other disk, whereby a greater bulk of insulating material will occur between these parts and necessity for the usual precise adjustment of one strain member relatively to the other be avoided.

Other objects and aims of this invention, more or less broad than those stated above, will be in part obvious and in part specifically referred to in the course of the following description of the elements, combinations, arrangements of parts and applications of principles constituting the invention; and the scope of protection contemplated will be indicated in the appended claims.

In the accompanying drawings, in which I have illustrated a merely preferred form of embodiment of the invention, and which are to be taken as a part of this specification; Figure 1 is a transverse, sectional view taken substantially on the plane of line 1—1 of Fig. 2, and looking in the direction of the arrow; Fig. 2 is a longitudinal, central, sectional view through the insulator shown in Fig. 1, and taken substantially on the plane of line 2—2 of Fig. 1, parts being shown in full; Figs. 3, 4, 5 and 6 are illustrative views showing the manner preferably employed for assembling the elements of the insulator, Fig. 3 illustrating one of the strain members with its respective disk in process of being moved to interlocking position. In Fig. 4 the first disk has been forced into interlocking relation, the second disk has been telescoped over the first strain member, and the second strain member interlinked with said first strain member prior to being dropped or forced downwardly into interlocking relation with the second disk, which final position is illustrated in Fig. 5. In Fig. 6 the parts are shown fully assembled and held in properly spaced relative position prior to the application of the enveloping insulating material; and Fig. 7 is a plan view of one of the anchoring disks.

In insulators of this class, considerable difficulty has been experienced by manufacturers in providing a relatively rigid connection between the strain members and the respective anchoring disks. Such connections as have been made heretofore have been either inefficient in the performance of their offices, or considerable expense has been added to the manufacture of the several individual parts and to the assembling of said parts, and hence the cost of the finished product has been considerably enhanced.

In the structure illustrated, I have shown a means whereby the strain members may be connected with their respective disks in a thoroughly satisfactory manner practically without increasing the expense incurred in the manufacture of the parts, and materially reducing the time necessary for assembling the parts, by improving the certainty with which the parts assume their proper co-related positions, and thereby decreasing the total cost of the finished prod-

uct. The amount of material comprised in the disks is considerably reduced.

I have also provided an improved construction whereby the parts are held firmly in interlocked position and the structure, moreover, is stronger and more efficient than any heretofore devised.

Referring to the drawings by numerals, 1 and 2 indicate the disks which are formed each with an opening 3 through the material thereof, having opposite end portions arranged substantially concentric with points spaced apart equi-distant from the axial center of the disk, for a purpose which will be apparent.

The strain members are indicated respectively by the numerals 4 and 5, the strain member 4 being adapted to be interlocked with the disk 1, and the strain member 5 with the disk 2. The centers of the end portions of the openings 3 in the disks are spaced apart substantially coincident with the centers of the legs 6 and 7 of the strain members. It will be understood that the two disks are arranged spaced apart in the structure, as shown in Figs. 2 and 6, and with the openings 3 in substantially right-angular relation, as best seen in Figs. 4 and 5, so that the legs of the strain member extending concentrically through the end portions of the opening 3 in one disk, will be in right-angular relation to the legs of the other strain member extending through the opening 3 in the second disk.

The opening 3 of each disk is formed with a pair of recesses 8, one in each of the side walls of the opening, said recesses being positioned and adapted to receive the enlarged end portions of the legs of the respective strain member. Each leg of the strain member is formed with a head 9 at its end adapted to engage one surface of the respective disk to prevent passage of the strain member through the recesses in one direction. Each of the legs is preferably further formed with a shoulder 10 adapted to engage a relatively opposite surface of the disk to prevent longitudinal movement of the strain member in the other direction. The shoulders 10 have relatively square surfaces facing toward the heads 9, and relatively inclined or cam surfaces 11 extending from the outer edge of said shoulders 10 and merging into the legs proper. The shoulders are formed on the outer sides of the legs so that they project away from each other, and it will be apparent that the inclined portions 11 will engage the walls of the recesses 8, while the strain member is being forced through the disk, and will spring the legs toward each other so that when the heads 9 reach the surface of the disk, then the shoulders 10 will spring or snap over the opposite face of the disk.

The heads 9 and the shoulders 10 coop-

erate with the opposite surfaces of the disk to positively prevent relative longitudinal movement between the strain member and the disk, so long as the spring action between the legs holds said legs pressed outwardly into engagement with the walls of the recesses 8. In order, however, that each of the legs of the strain member may be interlocked to a sufficient degree, with the disk, irrespective of the presence of the other leg, or of the spring action between said legs, I preferably form the heads 9 of a wedge-shape, flaring outwardly beyond the recesses 8, as best seen in Fig. 1, and adapted to be received within wedge-shaped depressions 12 formed in the surface of the disk, there being just sufficient play between the wedge-shaped walls of the head 9 and the wedge-shaped walls 13 of the depression 12 so as to permit assembling. The engagement between these walls positively prevents movement of the respective legs of the strain member transversely out of the recesses. The proportions of the parts are preferably such that the strain members must be forced into their interlocking positions. Considerable force is usually employed for this purpose so that the protruding corners of the material of both the strain members and the disks are mashed down in the operation. The material thus mashed increases the intimacy of the engagement between the parts and usually completely destroys any relative movement which might otherwise exist. This structure is especially valuable in instances where some force may be brought to bear, such as would tend to reduce the distance between the legs of the strain members and destroy the spring action, as for instance, when a considerable strain is placed upon the insulator sufficient to bend the loop end of the strain members so as to reduce the diameter of the connecting portion 14 between the legs, or in other ways. The peculiar wide flaring shape of the heads 9, projecting directly toward the periphery of the disk, serves an additional purpose. It will be noted that the body of material connecting the two halves of the disk is quite small and correspondingly incapable of withstanding any material twisting or bending strains. It will also be noted that a pull upon the strain members would be transferred to the disk at points spaced considerably from the outer edge of the disk, which outer edge portion is the portion which will offer the greatest resistance to the pull of the strain members, were it not for the fact that the heads 9 flare outwardly toward said outer edge portion for a sufficient distance to equalize the strains and prevent a tendency to buckle the disk.

In assembling the parts, one of the strain members, for instance 4, is inserted within

the recesses 8 of one of the disks, for instance the disk 1, and said disk is forced along the legs of said strain member and over the inclined portion 11 of the shoulders 10, forcing the legs toward each other, 70 and snapping into position between the shoulders 10 and the adjacent surface of the heads 9. The disk 2 is then dropped into position with the rounded end portions of the opening 3 substantially concentric 75 with the legs of the strain member 4, as in Fig. 4, and the second strain member, as 5, is interlinked through the strain member 4 in relatively inverted relation and dropped, or forced, downwardly so that its legs pass 80 through the recesses 8 in the disk 2 and concentrically through the rounded ends of the opening 3 of the disk 1 until the inclined portions 11 of the shoulders 10 on its legs pass through the recesses 8 on the disk 2 and 85 snap over the surface of said disk into the position in Fig. 5. Each strain member then stands relatively rigidly interlocked with its respective disk, and said disks are then separated to the position shown in Fig. 90 6, where they are held, by any suitable means, while the enveloping body of insulating material 15 is molded about them, entirely inclosing and filling all intricacies about and between the disks and inclosing a 95 portion of the strain members. This body of insulating material may be given any desirable exterior formation, but is preferably molded with suitable annular flanges as 16 and 17, the flange 16 being central and 100 preferably projecting outwardly, for a considerable distance, and forming, in effect, a disk surrounding the body 15, and the flanges 17 being arranged one at each side of the flange 16 and preferably flaring outwardly at an angle from said body portion 15. The flanges materially increase the surface distance between the exposed portion of the strain member 5, at one side of the body, and the exposed portion of the strain 110 member 4, at the opposite side of the body.

As many changes could be made in this construction without departing from the scope of the following claims, it is intended that all matter contained in the above description or shown in the accompanying drawing shall be interpreted as illustrative only and not in a limiting sense.

Having thus described my invention, what I claim as new and desire to secure by 120 Letters Patent, is:

1. In an insulator, the combination comprising an anchoring member, a single rod extending into engagement with said anchoring member and having integral formations thereon interlocking with co-operating formations integral with said anchoring member in such manner as to retain said rod against longitudinal movement in two directions relatively to said anchoring member, 125 130

and said interlocking formations on said rod and on said anchoring member serving also to retain said rod against relative transverse movement; and a body of insulating material within which said anchoring member is embedded.

2. In an insulator, the combination comprising an anchoring member; a U-shaped conductor arranged with its two legs extending into engagement with said anchoring member, each of said legs having integral formations thereon sprung into interlocked relation with coöperating formations integral with said anchoring member by relative spring action between said legs; each leg of said U-shaped conductor, when interlocked with said anchoring member, being held by said interlocking formations irrespective of the presence of the other leg or of the spring action between the legs in such manner as to be retained against longitudinal movement in two directions relatively to said anchoring member and being also held against relative transverse movement; and a body of insulating material within which said anchoring member is embedded.

3. In an insulator, the combination comprising an anchoring member having an opening formed through the material thereof; a U-shaped conductor arranged with its two legs projecting through said opening, each of said legs having integral formations thereon sprung into interlocked relation with coöperating formations integral with said anchoring member by relative spring action between said legs tending to spring said legs apart and into contact with the walls of the opening in said anchoring member, each leg of said U-shaped conductor, when interlocked with said anchoring member, being held by said interlocking formations irrespective of the presence of the other leg or of the spring action between the legs in such manner as to be retained against longitudinal movement in two directions relatively to said anchoring member and being also held against relative transverse movement; and a body of insulating material within which said anchoring member is embedded.

4. In an insulator, the combination comprising an anchoring member, a single rod extending into engagement with said anchoring member and having integral formations thereon interlocking with coöperating formations integral with said anchoring member in such manner as to retain said rod against longitudinal movement relatively to said anchoring member, and said interlocking formations on said rod and on said anchoring member serving also to retain said rod against relative transverse movement, said integral formations on said rod and anchoring member comprising shoulders on

said rod engaging relatively opposite surfaces of said anchoring member to prevent relative longitudinal movement of the rod, the anchoring member being formed with a recess to receive said rod, and shoulders on said anchoring member engaging said rod for retaining said rod in said recess to prevent relative transverse movement of the rod; and a body of insulating material within which said anchoring member is embedded.

5. In an insulator, the combination comprising an anchoring member, a single rod extending into engagement with said anchoring member and having integral formations thereon interlocking with coöperating formations integral with said anchoring member in such manner as to retain said rod against longitudinal movement relatively to said anchoring member, and said interlocking formations on said rod and on said anchoring member serving also to retain said rod against relative transverse movement, said integral formations on said rod and anchoring member comprising shoulders on said rod engaging relatively opposite surfaces of said anchoring member to prevent relative longitudinal movement of the rod, the anchoring member being formed with a recess to receive said rod, one of the shoulders on said rod being wedge-shaped, and said anchoring member having a wedge-shaped depression for receiving said wedge-shaped shoulder in such manner as to retain said rod in said recess to prevent relative transverse movement of the rod; and a body of insulating material within which said anchoring member is embedded.

6. In an insulator, the combination comprising an anchoring member; a single rod extending into engagement with said anchoring member and having integral formations thereon interlocking with coöperating formations integral with said anchoring member in such manner as to retain said rod against longitudinal movement relatively to said anchoring member, and said interlocking formations on said rod and on said anchoring member serving also to retain said rod against relative transverse movement, said integral formations on said rod and anchoring member comprising a head at the end of said rod engaging one side surface of said anchoring member, a laterally projecting shoulder on said rod engaging the opposite side surface of said anchoring member, said head and shoulder serving to prevent relative longitudinal movement of the rod, the anchoring member being formed with a recess adapted to receive the portion of said rod between said head and said shoulder, said head being wedge-shaped and said anchoring member having a wedge-shaped depression for re-

ceiving said wedge-shaped head in such manner as to retain said rod in said recess to prevent relative transverse movement of the rod; and a body of insulating material 5 within which said anchoring member is embedded.

7. In an insulator, the combination comprising an anchoring member having an opening formed through the material 10 thereof; a U-shaped conductor arranged with its two legs projecting through said opening, and means for locking said legs with said anchoring member in such manner as to prevent movement of said legs 15 toward each other and also to prevent relative movement of said conductor in both its longitudinal directions relatively to said anchoring member; and a body of insulating material within which said anchoring member 20 is embedded.

8. In a strain insulator, the combination comprising a disk-shaped member having an opening entirely within its peripheral edge, a substantially U-shaped strain member 25 extending partly within said opening, the ends of the strain member being provided with integral formations adapted for interlocking engagement with coöperating formations integral with the disk-shaped 30 member, whereby when said strain member and disk are assembled they are detachably locked against relative movement in all directions irrespective of any other parts of the insulator.

35 9. In a strain insulator, the combination comprising a pair of disk-shaped members disposed in opposed relation and each having an opening entirely within its peripheral edge, a pair of strain members extending 40 partly within said openings respectively and being fixed one to each of said disk-shaped members; each disk-shaped member and its respective strain member having integrally formed interlocking formations coöperating 45 between them whereby they are detachably locked against relative movement in all directions irrespective of any other parts of the insulator.

10. In a strain insulator, the combination

comprising a strain member and an anchoring member therefor, the strain member comprising a rod adapted to be slid past an edge portion of the anchoring member in being assembled with said anchoring member, means for interlocking said strain member 50 with said anchoring member to prevent relative movement of the strain member in two longitudinal directions when said strain member has reached a pre-determined position, and means yieldably maintaining said 55 interlocking parts in interlocked relation.

11. In a strain insulator, the combination comprising a strain member and an anchoring member therefor, the anchoring member having an opening therethrough, the 60 strain member being U-shaped and having substantially parallel leg portions, laterally 65 projecting extensions formed upon the free ends of each of said legs and projecting away from each other, the strain member 70 being adapted to be assembled with the anchoring member by being slid through the opening in said anchoring member until said lateral extensions engage against the rear face of the anchoring member to limit further sliding movement, and other extensions formed upon the legs of the strain member 75 to engage the forward face of the anchoring member to limit sliding movement of the strain member in the reverse direction. 80

12. In a strain insulator, the combination comprising an anchoring member having an opening therethrough, a U-shaped strain member having the inner ends of its legs projecting through said opening, and lateral extensions on the inner ends of said legs projecting into engagement with relatively opposite surface portions of the anchoring member to retain the anchoring member against relative movement longitudinally in two directions. 85 90

In testimony whereof I affix my signature in the presence of two witnesses.
